A. MACLACHLAN

DEODORIZING APPARATUS

Filed July 28, 1920

Inventor

ANGUS MACLACHLAN
By his Attorney
N. Dorsey Spencer

UNITED STATES PATENT OFFICE.

ANGUS MACLACHLAN, OF PERTH AMBOY, NEW JERSEY, ASSIGNOR TO MACLACHLAN
REDUCTION PROCESS CO., INC., OF NEW YORK, N. Y., A CORPORATION OF DELAWARE.

DEODORIZING APPARATUS.

Application filed July 28, 1920. Serial No. 399,589.

To all whom it may concern:

Be it known that I, ANGUS MACLACHLAN, a citizen of the United States, residing at Perth Amboy, New Jersey, have invented 5 certain new and useful Improvements in Deodorizing Apparatus, of which the following is a clear, full, and exact description.

My invention relates to a method for deodorizing gases which result from treatment 10 of waste organic substances, and more particularly the gases resulting from the treatment of garbage, tankage and the like, and an object of my invention is to provide a 15 simple and inexpensive method by which these gases are completely deodorized.

Great difficulty has been experienced in the past in effecting deodorization of such 20 gases, and apparatuses expensive to construct and operate have been proposed but these have not proved successful in operation.

An important feature of my invention consists in using SO_2 as a deodorizer, and 25 such SO_2 may be produced in any desired manner, as by burning sulphur and mixing the gas generated with the gases which are to be deodorized, these gases being under pressure or otherwise, and preferably steam 30 is mixed with the SO_2 gas. While my process may be performed in a great variety of ways and by the use of different forms of apparatus, for the purpose of illustrating a practical embodiment of my invention I 35 have shown one form of apparatus by which it may be successfully practiced.

Referring to the drawing, 1 indicates a receptacle which may be of a variety of shapes suited to the particular purpose for 40 which it is to be used. In this tank the waste organic substances may be treated by what is known as dry cooking, or the substances may be treated by boiling or steaming. 2 indicates a stack leading from the 45 receptacle 1, and through which the waste gases pass. I prefer to treat these gases, during their passage, through the stack, although they may be treated while in the tank, or they might be conducted to a separate chamber and there treated; and for this purpose I provide a sulphur burner indicated diagrammatically at 3. This sulphur burner may be of any desired construction—such, for instance, as that shown 50 in my application Ser. No. 302,243. A gas

conveyer 4 leads from this sulphur burner and enters the stack 2 through a suitable opening therethrough. The conveyor 4 has a restricted nozzle at 5, which projects into the stack and terminates adjacent a restricted portion 6 formed in the stack. Suitable means are provided whereby the SO_2 gas generated in the sulphur burner is delivered at the nozzle 5, where said gas mixes with the waste gases in the stack 2 and combines with them in such manner as to effect complete deodorization of the same. Stack 2 may be bent downwardly, as shown; and at some suitable point therein, as at 7, water may be sprayed into the stack 2 so as to 65 condense the gases, from which point 7 the condensed gases may be allowed to pass through a waste tank 8 which is in communication with a sewer. Such gases as are not condensable may pass into the atmosphere, but these as well as the gases which are condensable are completely deodorized by the treatment to which they have been subjected.

The SO_2 gas may be delivered under 70 pressure to the nozzle 5, and to do this I have shown a steam pipe 10 leading from a steam generator 11, the end of the pipe passing into the conveyor 4 through a nozzle 12, the steam acting to aspirate the SO_2 75 gas passing up the conveyor 4. Other means of delivering the SO_2 may of course be employed.

It is to be understood that the manner of procedure and the form of device for carrying out my improved process may be varied 80 to suit different conditions without in any manner departing from the spirit of my invention.

Having thus described my invention, what 85 I claim and desire to secure by Letters Patent is:

1. The method of deodorizing gases resulting from the treatment of waste organic substances, which consists in introducing 100 SO_2 and steam into the conduit along which said gases pass.

2. The method of deodorizing gases resulting from the treatment of waste organic substances, which consists in introducing 105 SO_2 and steam into the conduit along which said gases pass and subsequently cooling the mixture.

3. The method of deodorizing gases resulting from the treatment of waste organic 110

substances, which consists in introducing hot SO₂ and steam into the conduit along which said gases pass.

4. The method of deodorizing gases resulting from the treatment of waste organic substances, which consists in introducing hot SO₂ and steam into the conduit along which said gases pass and subsequently cooling the mixture.

10 5. In an apparatus of the character described, the combination with a tank in which waste organic substances are treated, a stack leading from said tank through which the gases resulting from the treatment of the substances pass, said stack having a restricted portion therein, and means

for introducing SO₂ under pressure into said stack adjacent said restricted portion.

6. In an apparatus of the character described, the combination with a tank in 20 which waste organic substances are treated, a stack leading from said tank through which the gases resulting from the treatment of the substances pass, said stack having a restricted portion therein, means for 25 introducing SO₂ into said stack adjacent said restricted portion, and means for spraying the gases in the stack subsequent to the treatment thereof with SO₂.

Signed at New York city, N. Y., this 30
14th day of June, 1920.

ANGUS MACLACHLAN.
